(57) **CLAIM**

We claim the ornamental design for an appliance heat controller, as shown and described.

DESCRIPTION

FIG. 1 is a top view of an appliance heat controller showing our new design.

FIG. 2 is a left side view of the appliance heat controller depicted in FIG. 1.

FIG. 3 is a right side view of the appliance heat controller depicted in FIG. 1.

FIG. 4 is a bottom view of the appliance heat controller depicted in FIG. 1.

FIG. 5 is a rear view of the appliance heat controller depicted in FIG. 1.

FIG. 6 is a front view of the appliance heat controller depicted in FIG. 1; and,

FIG. 7 is a top, front perspective view of the appliance heat controller depicted in FIG. 1.

The broken lines shown in the drawings are included for the purpose of illustrating portions of the article that form no part of the claimed design.
